UNITED STATES PATENT OFFICE.

JOSEPH C. EMLEY, OF MELROSE PARK, PENNSYLVANIA.

BRICK.

1,330,249.

Specification of Letters Patent. Patented Feb. 10, 1920.

Application filed April 12, 1917. Serial No. 161,618.

To all whom it may concern:

Be it known that I, JOSEPH C. EMLEY, citizen of the United States, and resident of Melrose Park, in the county of Montgomery and State of Pennsylvania, have invented certain new and useful Improvements in Bricks, of which the following is a specification.

The invention relates to bricks having vitreous or glass faces, and the object of the same is to provide the bricks with a backing or body part composed of heat-insulating material and adapted particularly for the outer walls of ovens and like structures, to prevent the escape of heat therefrom and to overcome deterioration of the outer surface thereof from an excessive temperature.

In describing the invention in detail, reference is had to the accompanying drawing, forming a part of this specification, and in which:

Numer 1 designates a vitreous facing member having the dovetailed ledge 2 projecting from the back thereof, and interlocking with the backing or body part 3 of the brick.

The vitreous facing member may be of well-known type, formed in the usual manner; and the backing or body part is composed of heat-insulating material consisting of infusorial earth mixed with a heat-

resisting cement binder, and molded together with the facing member to form a brick of conventional size adapted to be 35 bonded with adjacent bricks forming the main wall of the structure.

The mixture of infusorial earth and binder is proportioned to effect a close union of the associated parts without substantially detracting from the heat-insulating action of the cellular infusorial earth, which, as thus combined, serves by its non-conductivity to prevent the loss of radiant heat and as a protection to the vitreous facing member against an excessive temperature.

What I claim as my invention and desire to secure by Letters Patent, is:

1. A brick comprising a backing or body portion formed of infusorial earth united together by a suitable heat-resisting binder to form a cellular block, and a facing member of relatively harder material anchored in said block. 50

2. A brick comprising a body portion formed of infusorial earth united together by heat-resisting cement to form a cellular block, and a facing member of relatively harder material anchored in said block. 55 60

Signed at New York, in the county of New York and State of New York, this 10th day of April, A. D. 1917.

JOSEPH C. EMLEY.
